LAWN SPRINKLER

George L. Turner, Hickory Corners, Mich., assignor to
H. B. Sherman Manufacturing Company, Battle Creek,
Mich., a corporation of Michigan

Filed Aug. 24, 1964, Ser. No. 81,409

Term of patent 14 years

(Cl. D91—1)

FIGURE 1 is a rear perspective view of a lawn sprinkler showing my new design.

FIGURE 2 is a front perspective view thereof.

The hose section and coupling portion shown in broken lines, and the extending rod-like towing element shown in broken lines at the opposite end of each figure, are included for illustrative purposes only.

I claim:

The ornamental design for a lawn sprinkler, substantially as shown and described.
